FIG. 3

FIG. 2

FIG. 1

FIG. 4

Figure 1 is a front elevational view of a suction pump for removing fluids from body cavities showing our new design, the end of the intake tube being broken away for convenience of illustration.

Figure 2 is a right side elevational view thereof, the left side being substantially the same, a portion of the intake tube being broken away to indicate indefinite length.

Figure 3 is a rear elevational view thereof.

Figure 4 is a top plan view thereof, the bottom view being substantially plain and a portion of the intake tube being broken away to indicate indefinite length.

We claim:

The ornamental design for a suction pump for removing fluids from body cavities, substantially as shown and described.
